UNITED STATES PATENT OFFICE.

JACOB L. GORE, OF HUGO, OKLAHOMA, ASSIGNOR OF ONE-HALF TO JOHN M. WARREN,
OF HUGO, OKLAHOMA.

STATION-INDICATOR.

1,342,283.

Specification of Letters Patent.

Patented June 1, 1920.

Application filed August 8, 1918. Serial No. 248,896.

To all whom it may concern:

Be it known that I, JACOB L. GORE, a citizen of the United States, residing at Hugo, in the county of Choctaw and State of Oklahoma, have invented new and useful Improvements in Station-Indicators, of which the following is a specification.

This invention has reference generally to improvements in that class of inventions known as cards, pictures, and sign exhibiting, and more particularly relates to an improved station indicator.

The invention has for its principal aim and object to provide a device of the above mentioned character designed to be mounted at a convenient height in the front part of a railroad coach or street-car to indicate to the passengers within the coach or car the next station at which the train or car will stop, also the number of miles traversed as well as the distance to the final destination or end of the route, and the time the coach or car is due to arrive at its final destination.

More particularly the present invention consists in the provision of a casing in which is mounted a manually operable apron upon which is successively printed the names of the several stations or stops as they occur, while coöperating with these names is a sight glass in the cover for the casing through which the names of the stations or stops are successively and independently visible from a point exteriorly of the casing and within the vision of the passengers in the coach or car.

It is a more specific object of this invention to provide improved tension rollers co-operating with the apron and the main rollers for holding the apron substantially taut and in close relation with the sight glass in the cover as the apron is being turned from one roller to the other and in addition insure of the proper winding of the apron about the main rollers.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction here-

inafter described and the scope of the application of which will be indicated in the appended claim.

The invention is clearly illustrated in the accompanying drawings, in which:—

Figure 1 is a front elevation of the invention.

Fig. 2 is a vertical transverse section thereon.

Fig. 3 is a front elevation of the invention with the cover removed.

Fig. 4 is a longitudinally central sectional detail of the invention.

Fig. 5 is a fragmentary side elevation.

Similar characters of reference are employed in all of the above described views, to indicate corresponding parts.

Referring now, more particularly, there is provided a main casing indicated generally by the numeral 1 of a substantially rectangular configuration comprising a bottom 2 from which project opposed side walls 3 in turn connected by a rear wall 4 and a top 5, the front of the casing being removably closed by a hinged cover 6. A partition 7 is mounted transversely in the casing near the bottom thereof, while suitably mounted between the bottom of the partition is a drawer 8 for containing miscellaneous articles.

With a view toward providing the improved indicating means there is mounted transversely of the casing and in the side walls 3, an upper main roller indicated generally by the numeral 9 and a lower main roller indicated generally by the numeral 10. Each of these rollers are desirably formed of wood and have metallic trunnions 11 projecting from the ends thereof, the trunnions near one end are journaled in bearings 12 secured to the inner surface of one of the side walls by suitable fasteners 13, while the opposed trunnions 17 are journaled through bearings 15 which are secured to the opposite side wall 3 by suitable fasteners 16. Each bearing 15 is opposed to one of the bearings 12 and is secured across an opening in one of the side walls and it is in these openings that the projecting squared ends 18 of the trunnions 17 are positioned. An apron 19 is now provided and has its main portion windable about the rollers 9 and 10 and its respective ends secured to these rollers, while arranged transversely on the front face of the roller are indicia 20 indicative of the names of the stations or stops 110

along a certain route which the coach or car travels. The indicia of course, are arranged in a vertical row, while on opposite sides of the row of names 20 are rows of 5 indicia 21 and 22 indicating respectively the number of miles between each station and the beginning and end of the route.

Mounted in the central opening in the cover 6 is a sight glass 23 and it is through 10 this sight glass that the names 20 are successively visible while on opposite ends of the main sight glass 23 are small sight glasses 23^a and 24 through which the indicia 15 21 and 22 are respectively visible for indicating the number of miles between the station displayed and the station at the end of the route as well as the station at the beginning of the route. The front face of the cover is provided directly beneath the 20 sight glasses 23^a and 24 with the word "Miles," while also carried by the outer face of the cover beneath the words "Miles" are brackets 23' in which are insertable cards 24' adapted to contain the words "To 25 Hugo" and "From Hope," slideable respectively in the brackets 23' beneath the glasses 24'. Of course, when the train reaches its destination and is to return over the same route, the cards with the words "To Hope" 30 and "From Hugo" may be replaced by other cards having the words thereon "To Hugo" and "From Hope," as is apparent. The words "Next station is" are printed or affixed to the front face of the cover near the top 35 directly over the sight glass 23 for cooperating with the main indicia 20 which is indicative of the stations or stops along the route. A dial 25 is also mounted on the front face of the cover, while coöperating 40 with the dial are hour and minute hands 26 which are designed to be manually adjusted with respect to the indicia on the dial for indicating the time which the train is due to reach the end of the route. Above 45 the dial and on the front face of the cover may be printed the words "This train due." With a view toward providing improved means for assuring of the maintenance of the apron in close relation to the inner surface of the cover as it is being operated idle 50 rollers 27 and 28 have their respective ends journaled in the side walls in a position above and below the sight glass 23 the arrangement being indicated in Fig. 2. To 55 assure of the proper winding of the apron about the roller 9 and 10 other tension rollers 29 and 30 are employed and have their opposed trunnions 31 journaled in opposed pairs of slotted brackets 32 connected to 60 the inner surfaces of the walls 3 by suitable fasteners 33. Arcuate leaf springs 34 have their inner ends secured to the rear wall 4

by means of fasteners 35 and their outer curved portions yieldingly engaged against outer faces of the rollers 29 and 30 respectively for exerting tension on these rollers to in turn hold the rollers 29 and 30 against the apron as it is being wound on either of the rollers 9 and 10 for assuring of a proper winding thereof.

65

In actuating the device, a crank handle indicated by the numeral 36 is employed and has a portion thereof formed with a socket 37 for engagement with the reduced squared ends of either one of the trunnions 70 14 of the rollers 9 and 10. By the use of this key which is designed to be carried by one of the employees, either one of the rollers 9 and 10 may be rotated to cause the next 75 station or stop at which the train will stop 80 to be visible through the sight glass 23.

70

It is believed in view of the foregoing description that a further detailed description of the operation of the invention is entirely unnecessary. Likewise it is believed that 85 the advantages of the invention will be readily apparent.

What is claimed is:—

A device for the purpose specified embodying a main casing in the front face of 90 which there is formed an opening, rotatably idle rollers disposed above and below the opening, upper and lower main rollers carried within the casing and disposed above and below the plane respectively of the two 95 idle rollers, an apron traversing the idle rollers and passing before the said opening and winding upon the two main rollers, means for rotating either main roller to move the apron in one or the other direction, slotted brackets carried in the main casing on opposite sides of the latter and disposed one pair below the upper main roller and the other pair above the lower main roller, tension rollers journaled in said 100 slotted brackets and bearing upon those portions of the apron wound on the two said main rollers, the slotted brackets providing for the movement of the axis of rotation of said tension rollers toward and away from 105 the main rollers to provide for their increase in diameter due to the winding thereon of the apron, and arcuate leaf springs secured to the back walls of the casings and bearing upon the peripheries of the tension rollers at points diametrically opposite the main rollers to preclude too free movement of the tension rollers and to maintain them in contact with those parts of the apron on the main rollers.

105

With a view toward providing improved means for assuring of the maintenance of the apron in close relation to the inner surface of the cover as it is being operated idle 110 rollers 27 and 28 have their respective ends journaled in the side walls in a position above and below the sight glass 23 the arrangement being indicated in Fig. 2. To 115 assure of the proper winding of the apron about the roller 9 and 10 other tension rollers 29 and 30 are employed and have their opposed trunnions 31 journaled in opposed pairs of slotted brackets 32 connected to 120 the inner surfaces of the walls 3 by suitable fasteners 33. Arcuate leaf springs 34 have their inner ends secured to the rear wall 4

115

120

In testimony whereof I affix my signature.

JACOB L. GORE.
